UNITED STATES PATENT OFFICE.

GEORGE A. KIMBREL, OF AVONDALE, COLORADO.

DITCHING-MACHINE.

1,139,190.

Specification of Letters Patent. Patented May 11, 1915.

Application filed December 2, 1913. Serial No. 804,321.

To all whom it may concern:

Be it known that I, GEORGE A. KIMBREL, a citizen of the United States, residing at Avondale, in the county of Pueblo and State of Colorado, have invented new and useful Improvements in Ditching-Machines, of which the following is a specification.

This invention relates to ditching machines and it consists in the novel features 10 hereinafter described and claimed.

An object of the invention is to provide a machine of the character indicated comprising a wheel mounted frame supporting a trunk in an inclined position. A conveyer belt is mounted for movement along the trunk and means is provided for operating the belt from the supporting wheels of the frame. At the lower end of the said trunk is located a dirt gatherer with a pilot conveyer band belt leading from the same to the receiving end of the first mentioned elevator belt. Means is provided for operating the pilot belt from the operating mechanism of the said elevator belt. A supplemental frame is pivotally supported upon the axle of the machine and extends in advance of the dirt gatherer. Levers are pivoted upon the supplemental frame and are connected with the dirt gatherer. The said levers may 20 be swung to raise or lower the dirt gatherer with relation to the surface of the ground. Standards are movably mounted at the forward portions of the supplemental frame and may be adjusted vertically to regulate 25 the depth at which the dirt gatherer will operate below the surface of the soil. A shiftable clevis is mounted at the forward portion of the supplemental frame.

A second trunk is pivotally mounted at 40 the rear portion of the main frame of the machine, and means is provided for swinging the last mentioned trunk to dispose the same at a desired angle with relation to a horizontal and also to position the same at 45 either side of main frame of the machine.

A conveyer belt is mounted for movement along the last mentioned trunk and means is provided for operating the last mentioned belt from the supporting axle of the machine. Also this last mentioned means includes mechanism for reversing the movement to the last mentioned belt so that either of the two runs of the belt may be used for conveying the dirt beyond the side 55 of the frame of the machine.

In the accompanying drawings:—Figure

1 is a top plan view of the ditching machine. Fig. 2 is a side elevation of the same. Fig. 3 is a longitudinal sectional view of the same. Fig. 4 is a rear end view of the same 60 with parts broken away. Fig. 5 is a transverse sectional view of a forward portion of the same. Fig. 6 is a plan view of mechanism located at the intermediate portion of the same. Fig. 7 is a detailed fragmentary 65 view of a forward portion of the same showing parts in section.

The ditching machine includes a main frame 1 in which is journaled an axle 2.

Ground or supporting wheels 3 are journaled upon the ends of the axle 2 and are provided at their inner side with clutch members 4.

Clutch members 5 are slidably mounted upon the axle 2 but are constrained to rotate with the same and the outer ends of springs 6 bear against the inner surfaces of the clutch members 5 and are under compression with a tendency to force the said clutch members 5 toward the clutch members 4. Any suitable means may be provided for moving the clutch members 5 away from the clutch members 4 and for positively holding them out of engagement with the said clutch members 4 against the 75 compression of the springs 6. When the clutch members 5 are free to move under the compression of the springs 6 toward the clutch members 4 and the ground wheels 3 rotate to carry the machine in a forward direction the clutch members 4 engage the clutch members 5 whereby the axle 2 is caused to rotate in unison with the wheels 3. However should one of the ground wheels 3 80 rotate in a backward direction as for instance when the machine is being turned around the clutch member 4 attached thereto may escape the adjacent clutch member 5 and consequently if the axle 2 is rotated at all it is turned through the engagement of 85 the other clutch member 4 and the member 5.

The axle 2 is also journaled in bearings 7 against the outer sides of which the springs 6 may bear and the rear end of a supplemental frame 8 is fixed to the bearings 7. The frame 8 is provided at its forward portion with guides 9 which slidably receive standards 10. Ground wheels 11 are journaled at the lower portions of standards 10. 100 The standards 10 are provided at their rear sides with teeth 12 and brackets 13 extend

from the forward portion of the frame 8 along the said standards. A shaft 14 is journaled for rotation in the brackets 13 and carries gear wheels 15 which mesh with the teeth 12 of the standard. Therefore it will be seen that by rotating the shaft 14 the gear wheels 15 meshing with the teeth 12 will cause the standards 10 to move vertically in the guides 9. Inasmuch as the ground wheels 11 are adapted to travel along the surface of the soil it will be seen that by shifting the standards 10 as above indicated the forward portion of the supplemental frame 8 may be raised or lowered with relation to the surface of the ground.

A clevis 16 is mounted for movement transversely of the forward portion of the supplemental frame 8 and a shaft 17 is journaled in the lower portion of the said clevis. The shaft 17 carries a gear wheel 18 which meshes with a set of gear teeth 19 provided at the under side of the forward portion of the supplemental frame 8. The supplemental frame 8 is further provided with another set of gear teeth 20 with which a gear wheel 21 meshes. The gear wheel 21 is journaled upon the clevis 16. By rotating the shaft 17 the gear wheel 18 meshing with the teeth 19 will move the clevis 16 from one side toward the other side of the supplemental frame 8 and the gear wheel 21 meshing with the teeth 20 will prevent the clevis from binding upon the forward portion of the frame 8 during such shifting movement. A tongue 22 is mounted upon the forward portion of the supplemental frame 8. In operation the draft animals are connected with the clevis 16 in any suitable manner and by shifting the clevis with relation to the frame 8 as above indicated the draft or pull from the draft animals may be shifted to one side or the other of the machine.

A forwardly and downwardly inclined trunk 23 is mounted upon the main frame 1 and the said trunk carries at its lower end a dirt gatherer 24. Levers 25 are fulcrumed at the sides of the supplemental frame 8 and links 26 pivotally connect the working ends of the said levers with the dirt gatherer 24. Therefore it will be seen that when the ground wheels 11 are in contact with the surface of the ground the upper ends of the levers 25 may be swung rearwardly until they come in contact with the forward portion of the main frame 1. During this swinging movement of the levers 25 the dirt gatherer 24 is lowered. When the power ends of the levers 25 are swung in a forward direction the links 26 are moved vertically or longitudinally in a downward direction whereby the dirt gatherer 24 is lowered with relation to the surface of the soil.

A shaft 27 is journaled intermediate the

ends of the trunk 23 and carries at each end a gear wheel 28 which gear wheels mesh with gear wheels 29 mounted upon the axle 2. Sprocket wheels 30 are fixed to the shaft 27 adjacent the inner surfaces of the sides of the trunk 23 and engage the links of chains 31 which are trained to move along the trunk 23.

A conveyer belt 32 is connected at its edges to the chains 31 and the said belt carries upon its outer sides cross slats 33 positioned at suitable intervals apart.

A roller 34 is journaled at the upper end of the trunk 23 and the belt 32 passes around the said roller.

Sprocket wheels 35 are located at the ends of the roller 34 and the chains 31 pass around the said sprocket wheels.

A roller 36 is journaled for rotation at the lower forward end of the trunk 23 and the belt 32 passes around the last mentioned roller.

Sprocket wheels 37 are located at the ends of the roller 36 and the chains 31 pass around the said sprocket wheels 37.

Supporting sprocket wheels 38 are journaled at suitable intervals along the sides of the trunk 23 and are adapted to support the upper run of the chains 31.

A lower roller 39 is journaled upon the dirt gatherer 24 and an upper roller 40 is also journaled upon the said gatherer.

A pilot belt 41 is trained around the rollers 39 and 40.

Sprocket wheels 42 are fixed with relation to the roller 39 and sprockets 43 are fixed with relation to the roller 36.

Sprocket chains 44 are trained around the sprocket wheels 42 and 43.

Therefore it will be seen that as the gear wheel 29 rotates with the axle 2 the said gear wheel will rotate the gear wheels 28 and shaft 27. Inasmuch as the chains 31 engage the sprocket wheels 30 the said chains will be moved and the upper run of the belt 32 will be moved rearwardly along the trunk 23. At the same time the sprocket chains 44 will move the upper run of the belt 41 in a rearward direction. Therefore as the dirt gatherer 24 encounters and accumulates the dirt the same is forced rearwardly upon the upper run of the pilot belt 41 which carries it back and deposits it upon the upper run of the belt 32. The said belt carries the dirt up to the rear end of the trunk 23. A chute 45 is mounted at the upper rear end of the trunk 23 and the dirt is deposited upon the said chute.

Standards 46 are mounted upon the rear portion of the frame 1 under the rear part of the trunk 23 and a shaft 47 is adjustably mounted in the said standards. The said shaft 47 is held against rotation and in an adjusted position by set screws 48 which pass through the said standards and impinge

against the said shaft. Sprocket wheels 49 are loosely mounted on the shaft 47 and sprocket wheels 50 are fixed to the axle 2. Sprocket chains 51 are trained around the sprocket wheels 49 and 50 and serve as means for transmitting rotary movement from the axle 2 to the sprocket wheels 49 which are loosely mounted upon the shaft 47. Beveled gear wheels 52 are fixed to the inner sides of the sprocket wheels 49 and are spaced from each other by a sleeve 52¹. By loosening the set screws 48 the shaft 47 may be adjusted longitudinally and shoulders 53 carried by the said shaft will engage the sides of the sprocket wheels 49 whereby the said sprocket wheels and the beveled gear wheels 52 are shifted transversely of the frame 1.

Spaced brackets 54 are mounted upon the rear portion of the frame 1 and a shaft 55 is journaled in the said brackets. A beveled gear wheel 56 is mounted at the forward end of the shaft 55 and either one of the beveled gear wheels 52 may be moved into engagement with the gear wheel 56. A trunk 57 is pivotally mounted upon the shaft 55 and chains 58 are mounted for movement along the said trunk. Sprocket wheels 59 are fixed to the shaft 55 and engage the links of the chains. A belt 60 is connected at its edges with a sprocket chain 58 and is provided upon its outer surface with cross slats 61. Suitable sprocket wheels 62 are journaled at intervals along the trunk 57 and serves to assist in supporting the chains 58. The receiving end of the trunk 57 is located under the delivery edge of the chute 45.

A circular guide 63 is fixed to the rear portion of the frame 1 adjacent the rear standard 54 and the guide is provided with a circular set of teeth 64.

A shaft 65 is journaled in the trunk 57 and is provided at its rear end with a crank handle 66. Gear wheels 67 are fixed to the shaft 65 and mesh with the teeth 64. Therefore it will be seen that using the handle 66 and rotating the shaft 65 the gear wheels 67 in mesh with the teeth 64 will swing the trunk 57 so that its outer end may be raised or lowered or its outer end may be moved from one side of the frame 1 to the opposite side. Gear wheels 68 are loosely journaled at the opposite sides of the trunk 57 and also mesh with the teeth 64 and serve as means for steadyng the trunk 57 in its position with relation to the guides and the standards 54.

It is to be understood that when the trunk 57 is disposed at one side of the frame 1 the upper run of the belt 60 is caused to move 60 from over the frame 1 beyond the edge thereof so that the dirt deposited upon the said belt is conveyed to one side of the machine. When the trunk 57 is turned over so that the other run of the belt 60 is brought to an 65 uppermost position the shaft 57 is moved so that the beveled gear wheel 56 meshes with the proper gear wheel 52 in order to cause the upper run of the belt 60 to travel in an outward direction with relation to 70 the frame 1.

Therefore it will be seen that a machine of simple and durable structure is provided for elevating and conveying the dirt during the operation of cutting a ditch and the parts 75 may be so proportioned as to cut ditches of comparatively small or great transverse breadth as may be required.

Having described the invention what is claimed is:—

1. A ditching machine comprising a wheel mounted frame, an elevator mounted upon the frame, means for operating the elevator from the wheels, a trunk pivotally mounted upon the frame at the delivery end of the 85 elevator, and having its delivery end free to be swung to one side or the other of the axis of the pivot a conveyer belt mounted for movement along the trunk, means for moving the conveyer belt from the supporting 90 wheels and means for swinging the trunk to position its delivery end beyond either of the two sides of the main frame whereby material may be deposited by the elevator on either of two runs of the belt. 95

2. A ditching machine comprising a wheel mounted frame, an elevator mounted upon the frame, means for operating the elevator from the wheels, circular guides mounted upon the frame, a trunk pivotally mounted 100 between the guides, said guides having circular sets of teeth, a shaft journaled upon the trunk and provided with gear wheels which mesh with the teeth, a belt mounted for orbital movement along the trunk, means 105 for operating the belt from the supporting wheels and shiftable to cause the runs of the belt to move in either of two directions.

In testimony whereof I affix my signature in presence of two witnesses.

GEORGE A. KIMBREL.
